UNITED STATES PATENT OFFICE.

WILLIAM D. HUNT, OF BRANDON, WISCONSIN.

END-GATE.

SPECIFICATION forming part of Letters Patent No. 366,107, dated July 5, 1887.

Application filed February 28, 1887. Serial No. 229,207. (No model.)

To all whom it may concern:

Be it known that I, WILLIAM D. HUNT, of Brandon, in the county of Fond du Lac and State of Wisconsin, have invented certain new and useful Improvements in Wagon-Irons; and I do hereby declare that the following is a full, clear, and exact description thereof, reference being had to the accompanying drawings, and to the letters of reference marked thereon, which form part of this specification, in which—

Figure 1 is a perspective view of a portion of a wagon-body and its top box or body having my invention applied. Fig. 2 is a side view of the invention detached. Fig. 3 is a front view of the same.

This invention relates to improvements in wagon-bodies, and has especial reference to means for holding and receiving the end-gates 20 of the wagon, and to also hold the supplementary or top box placed above the ordinary body of the wagon to increase the holding capacity of the same.

The invention consists in the peculiar and 25 novel construction of the parts hereinafter described, and specifically designated in the claims.

Referring to the accompanying drawings by letters, A designates the side-board of a wagon-30 body of ordinary construction. At the proper point on board A, near the end thereof, is bolted a flanged metal strap, B, the flanges b b of which stand inward from the side edges of the strap, as shown, and this strap is provided 35 at its lower end or formed with a rounded and threaded portion or bolt, b', which is adapted to pass through the wagon-body floor to secure the side-board in position thereon. The flanges b b, however, only extend from the 40 top of the strap to the floor of the body, where they end, the strap being then extended into the bolt b'. The space between the flanges b b is sufficiently wide to receive the edges of the end-gate of the wagon, as shown. Near 45 the top of the inner flange, b, I form a short outstanding flange or stud, C, which extends forward in a direction parallel with the length of board A. This stud C is integral with its flange, and therefore with strap B. If desired, both flanges b b may be provided with 50 studs C, which would in that case stand in the

same line but in opposite directions. The studs C serve a purpose hereinafter explained.

D designates the side-board of a supplementary body or box corresponding in shape 55 with the wagon-body and placed above the same, as usual. To the side-board D, at a point directly above and corresponding with the position of the strap B, I secure a strap or iron, E, which is bolted to board D, and the side 60 edges of which are turned inward, forming flanges e e, corresponding with flanges b b of part B. The flange e of iron E, that stands above the flange b, having stud C, is formed with a depending lug, F, which is of proper 65 length and size to fit snugly between stud C and board A, as shown. The straps B and irons E being secured to their respective bodies at the four corners thereof, it is evident that when placed in position upon the wagon-body 70 the box will be securely held thereon. If desired, both flanges e e may be provided with lugs F, to engage the corresponding studs C on flanges b b.

It will be observed that when the parts are 75 adjusted as described the flanges b b and e e form a continuous channel or groove for receiving and holding the boards of the end-gates of the wagon-body and its box. It will further be observed that by means of studs C 80 and lugs F no bracing rods for the sides of the box are necessary, since, when adjusted in position, it will be impossible to force outward the side-boards of the box without simultaneously forcing apart the side-boards of the 85 lower body, as the parts B and E form a rigid connection between the side-boards A and D of the body and box, as described.

I am aware that it is not broadly new to employ irons upon the bodies of wagons to 90 form the end-gate guides for the same, and am also aware that upper irons have been used to form a continuation of the end-gate guides on the supplementary body or box. Therefore I do not claim such broadly; but

What I do claim is—

1. The combination, with the main body of a wagon having the flanged straps forming guideways for the end-gates, and provided at the upper ends of their flanges with horizontally-extending stud or studs, of the flanged irons secured to the supplementary body and—

having their flanges provided with downwardly-extending lugs adapted to engage with the studs and flange of the straps on the main body, all constructed and arranged substantially as and for the purpose specified.

2. The combination of the strap B, having flanges *b b* and stud C on these flanges, and adapted to be secured to the main body of a wagon with the irons E, having flanges *e*, and depending lugs F from flanges *e*, adapted to engage with the straps B by studs C thereof, and secured to the supplementary wagon-body, all constructed substantially as and for the purpose specified.

15 3. The combination, with the side-board A of the main wagon-body, of the straps B, having flanges *b b*, and depending threaded por-

tion *b'*, substantially as described, and studs C, standing from the flanges *b*, as described, of the irons E, secured to the side-boards D of the supplementary body, and having flanges *e e*, forming a continuation of flanges *b b*, and depending lugs F, adapted to engage with straps B between studs C and board A, to hold the supplementary body in position, all 20 25 constructed and arranged substantially as shown, and for the purpose specified.

In testimony that I claim the foregoing as my own I affix my signature in presence of two witnesses.

WILLIAM D. HUNT.
